UNITED STATES PATENT OFFICE

BRODERICK HASKELL, OF FRANKLIN, PENNSYLVANIA, ASSIGNOR TO DAVIS BRAKE BEAM COMPANY, OF JOHNSTOWN, PENNSYLVANIA, A CORPORATION OF PENNSYLVANIA

SAFETY LOOP FOR CONNECTING RODS

Application filed April 1, 1930. Serial No. 440,744.

The invention relates to safety loops for the connecting rods of brake gears in railway car trucks.

The safety loops now used, or heretofore suggested, for this purpose are formed of rigid metal bars, or plates, or of wire having a limited amount of resiliency, and, being so formed, they either break or become materially deformed when struck by road bed obstructions. If they break, they become useless as safety loops, and accordingly the connecting rods may, with disastrous consequences, fall upon the road bed if the rod or other brake gear supporting connections should fail. On the other hand, if the loops become materially deformed they may seriously interfere with the normal operation of the brakes.

The object of this invention is to provide a safety loop which cannot be broken or deformed by striking road bed obstructions, or when encountering other exigencies in service, and which accordingly remains continuously in proper form to support a connecting rod when occasion arises for its doing so.

The invention is illustrated in the accompanying drawings, of which Fig. 1 is a combined transverse sectional view of a spring plank of a railway car truck and a side elevation of a safety loop embodying the invention; Fig. 2 a plan view of the construction shown in Fig. 1; and Figs. 3 and 4 views taken on the planes indicated by the lines III—III and IV—IV, Fig. 1.

According to this invention, there is attached to a suitable supporting member of a railway car truck, preferably to its spring plank, a safety loop which is so limber and flexible that regardless of how it may be distorted when struck by road bed obstructions, or otherwise, it is not broken, and returns to its normal position for supporting a connecting rod when occasion for this arises. Furthermore, because of the limber and flexible characteristic of the loop, it does not become bent to impair or interfere with the normal and free operation of the brake gear.

Having reference to the illustrative embodiment of the invention, a spring plank 1 of a railway car truck has suitably attached

to it a pair of safety loops 2 and 3 which receive a connecting rod 4 of a brake gear. These loops are preferably formed of flexible stranded metal cables. While they may be variously attached to the spring plank, the latter is preferably provided with lugs for this purpose. As shown in Fig. 3, the spring plank has a lug 5, formed of a short section of an angle, attached to it by rivets 6. The outstanding leg of the lug is provided with perforations 7, which receive the ends of loops 2, the perforations being preferably rounded at their lower ends to prevent the loop from being cut when flexed. To attach the ends of the loops to the lug, each end is preferably surrounded by a sleeve 8 which rests upon the outstanding lug of angle 5, and to which the upper end of the loop is welded, as at 9.

Ordinarily, both safety loops for the truck will be the same. However, to illustrate a modified form of attachment of a loop to a spring plank, loop 3 shown in Fig. 4 has its ends attached to separate lugs 10, each connected to the flange of the spring plank by a rivet 11. In this embodiment of the invention, the ends of the loops extend through perforations 12 in the outstanding legs of lugs or channels 10, and are welded, as at 13, directly to the upper faces of these legs rather than to sleeves or other members, as in the form of Fig. 3.

In case the lower end, or any other portion of a loop provided according to this invention, is in any way distorted, it freely yields without becoming broken or in any way otherwise impaired, and promptly returns to its normal position for supporting a connecting rod when that becomes necessary.

According to the provisions of the Patent Statutes, I have explained the principle and operation of my invention, and have illustrated what I now consider to represent its best embodiments. However, I desire to have it understood that, within the scope of the appended claims, the invention may be practiced otherwise than as specifically illustrated and described.

I claim as my invention:

1. In a railway car truck having a spring

plank, a lug attached to said spring plank, and a safety loop suspended from said lug for receiving a connecting rod of a brake gear, said loop being formed of a flexible stranded metal cable.

2. In a railway car truck having a spring plank, a lug attached to said spring plank and provided with a pair of perforations, and a safety loop formed of a flexible stranded metal cable having its ends extending through said perforations and engaged by said lug, said loop being adapted to receive a connecting rod of a brake gear.

3. In a railway car truck having a spring plank, a lug attached to said spring plank and provided with a pair of perforations, a safety loop formed of a flexible stranded metal cable having its ends extending through said perforations, and sleeves surrounding and welded to said loop ends for supporting the loop to receive a connecting rod of a brake gear.

In testimony whereof, I sign my name.
BRODERICK HASKELL.
